UNITED STATES PATENT OFFICE.

FRANK GRAY, OF CHICAGO, ILLINOIS.

VALVE AND ALARM.

SPECIFICATION forming part of Letters Patent No. 693,820, dated February 11, 1902.

Application filed July 13, 1899. Serial No. 723,671. (No model.)

To all whom it may concern:

Be it known that I, FRANK GRAY, a citizen of the United States of America, and a resident of Chicago, Cook county, Illinois, have 5 invented a certain new and useful Improvement in Valves and Alarms, of which the following is a specification.

This invention relates to means for sounding emergency alarms in automatic fire-extinguishing systems and also to improvements in the valve apparatus and alarm mechanism employed for such purposes.

In sprinkler systems, whether wet or dry, it is desirable to sound an alarm whenever 15 fuses are blown out and to keep this alarm going continuously until the emergency is passed. It is also important that any attempt to tamper with the main valve controlling the fluid-supply for the purpose of rendering the 20 system inoperative should be immediately signaled by the sounding of a persistent alarm and that the means controlling this alarm should be of such nature that they cannot be operatively disconnected except at the point 25 where the alarm is to be sounded, any attempt to this end precautionary to tampering with the valve only resulting in the sounding of the alarm. The vehicle that I employ for transmitting to the signaling apparatus the 30 actuating effect of the original causation is the fluid-pressure in the pipes of the system beyond the main valve.

In dry-pressure systems a body of air is confined in the sprinkling-pipes above the main 35 valve and held against the pressure of the water by a supplementary or differential check-valve. This body of air is under less pressure than the water-pressure until a plug is blown, when there is first a fall in pressure 40 and then the water rushing in at once materially increasing the pressure in the pipes. Therefore to sound an alarm indicating that the sprinkling system is in active operation the alarm apparatus must be held out of action by the normal or static pressure, but caused to sound by a rising pressure; but if the main valve is closed, cutting off the water-supply, and a fire started the first fuse 45 that melts will release the compression on the air, and there will be a fall in pressure to which the alarm mechanism must also be susceptible. If, then, the valve is closed and a

55 fuse opened with the idea that the alarm will be cut out, the effect will only be to accelerate the time of its sounding. If a fuse is opened before the valve is closed, the water will rush in and the alarm sound, and although the valve should be immediately closed the ensuing reduction of pressure will only result in further operating it, or if a bypass is placed around the differential valve 60 and a drainage-passage opened by the act of shutting the main valve any closure of said valve will be followed by a reduction in pressure in the air-loaded sprinkler-pipes and consequent ringing or sounding of the alarm. 65

In wet pipe systems the water is held in the pipes beyond the main valve normally at its highest pressure or a pressure effective for immediate operation, and the first effect 70 of blowing a fuse, or cutting a pipe, or opening a drain is to lower the pressure. Therefore the alarm must be such and so connected that the slightest reduction in pressure from this normal will cause it to sound; but wet 75 systems are often changed to dry and dry to wet without change in the installation, or at least without material change. Hence it is still of consequence that the alarm mechanism should be instantly operative whether 80 the pressure is reduced or increased.

The object of the invention is therefore, primarily, to provide for the sounding of an alarm upon any variation of pressure in the pipes beyond the main cut-off valve opening 85 from the supply-pipe, whether that variation be rising or falling; secondly, to guard against effective tampering by causing the continuous sounding of an alarm by either increase or decrease of pressure consequent 90 upon such an attempt from the closing of the main valve until said valve is again fully opened; thirdly, to make the sounding of such alarm concurrent with the incipient closing movement of the main valve; fourthly, to so 95 construct the alarm-gage that it will be operated in either a wet or a dry system and by either a decrease or an increase of pressure, and, fifthly, to secure ease and sensitiveness of operation in the alarm-gage. 100

Various other objects of the invention will appear from the ensuing description when read in the light of the accompanying drawings, in which—

Figure 1 is an elevation of a wet pipe automatic fire-extinguishing system embodying my invention. Fig. 2 is a horizontal section through the main-valve casing on the line 2 2 5 of Fig. 1, showing the valve in the incipiency of its closing movement and communication established with a pipe leading to a pressure-gage alarm. Fig. 3 is a transverse section on the irregular line 3 3 of Fig. 2, the valve 10 being closed. Fig. 4 is a front elevation, partly broken away, of the pressure-gage alarm and accessory devices. Fig. 5 is a transverse section, enlarged, through the gage-box on the line 5 5 of Fig. 4; and Figs. 6 and 15 7 are details.

A represents the supply-pipe of an automatic fire-extinguishing system; A', the riser-pipe leading upward therefrom; A², the main-valve casing between the two, and A³ horizontal sprinkler-pipes reaching outward from the riser-pipe, and having fuses *a*, which blow with an abnormal rise in temperature. From the "distributing-pipes," in which term may be included everything above the main 25 valve—as the valve-chamber, the riser, and the sprinkler pipes—a pressure or alarm pipe (one or more) is led to a distant station, where it connects with a pressure-gage controlling the switching or throwing device of alarm apparatus in such manner that at the normal or static pressure of the distributing-pipes or that member thereof from which the alarm-pipe is led, which is the pressure in the alarm-pipe, the switch will be retained, as it were, 30 open and no alarm will be sounded, but with either an increase or a reduction of pressure the switch will be closed and the alarm set in operation, whatever its nature.

Preferably I employ an electrical alarm 40 (designated generally at B) operated by a dry battery, and that which I have devised and propose to use for this purpose is as follows: To a supporting-board C is secured the box or casing C' of a pressure-gage, which, except 45 in the features hereinafter distinguished, may be of ordinary construction. A coupling C² affords means for connecting the gage to the alarm-pipe, whereby its pointer C³ may indicate the pressure therein. Now if the pointer 50 were permanently connected with one pole of the battery of an electric alarm and two contacts connected with the other pole were located one on each side of the dial-mark indicating the static pressure in the alarm-pipe 55 of distributing-pipes—say sixty pounds for wet pressure or thirty pounds for dry—it is evident that with either an increase or a decrease of pressure the pointer would act as a circuit-closer and cause the alarm to sound; 60 but as the static pressure adopted is determined by exigencies and may be greater or less than the figures suggested and as the alarm is intended to be used with wet and dry systems indiscriminately, these contacts 65 would have to be capable of adjustment, so as to be shifted according to the pressure de-

termined. It is simpler, however, and more advantageous, instead of making the pointer itself the circuit-closer, to place a fixed contact upon the dial D and arrange a double-contact circuit-closer movable with and adjustable relatively to the pointer to coöperate with said fixed contact. Advisably such circuit-closer is a disk E, mounted upon and adjustable around the insulated contact-post 70 E', which forms a continuation of the gage-spindle E² and also carries the pointer. The disk has a gap *e* in one side, with opposing beveled or knife edges *e'* and *e''*, and, being fitted over the reduced upperend of the contact-post by its central bore *e*³, is clamped by means of the binding-nut E³ with its gap in any requisite radial position. The fixed contact is herein shown as composed of two opposing springs F' and F², electrically connected with the dial D by means of their supporting-bracket F³ and extending inward toward the circuit-closer, so that their counter-setting contact-pins *f'* and *f''* may meet in the gap on a plane connecting the knife-edges of said 85 closer. Thus any movement of the closer to right or left with the pointer will force one or the other knife-edge between said contact-pins, establishing electrical connection, and if the movement is continued the connection 90 will also continue, as pins will ride upon the plane surface of the closer-disk, extending around from one side of the gap to the other. The operation will be the same, though not entirely so permanently reliable, if one of the 95 springs of the fixed contact is dispensed with.

G and G' represent the cells of a dry battery mounted upon the supporting-board. The positive pole of cell G is connected by lead *h* with the insulated binding-post H, set 105 through the wall of the gage-box, and thence by spring-contact H' with the insulated contact-post of the gage-spindle, and through this to the circuit-closer. The dial D is supported upon insulating-posts J, and the negative pole of cell G' is connected with said 110 dial by lead *k* and insulated binding-post K, also set through the wall of the gage-box.

L is an alarm-bell connected in series with the battery-cells on the other side of the circuit. 115

In order to set the alarm ready for action, the pressure is first established and then the circuit-closer is adjusted to center its gap upon the fixed contact while the pointer is indicating such pressure. Thereafter any change in pressure, whether up or down, and however caused, will bring one or the other knife-edge against the fixed contact, close the 120 circuit, and sound the alarm.

By forming the circuit-closer as a gapped disk and mounting it upon and adjusting it around the spindle which carries the pointer, so as to revolve with said pointer, or, in other words, bringing it close to the axis of movement of the pointer, a long contact-surface 125 is secured in small space, and adverse lever-

age is reduced to a minimum, a matter of importance in pressure-gages, which are, as a rule, weak in return to zero.

Coming now more particularly to the apparatus for inducing a change in pressure and consequent sounding of the alarm by wilful disturbance of the main valve, M is a relief-pipe leading from the valve-casing A² and connecting with the chamber therein above the valve. Communication may be established between this relief-pipe and the main drain-pipe M' by means of a branch pipe m and stop-cock m' at a point beneath and removed from the main valve and its point of manual operation, so that it may be drained when necessary. It may also have a valved stub m², for packing in an independent pressure. The relief-pipe may terminate in an alarm mechanism B' of the nature of that above described and located at a distant station.

N is the main valve, formed as a slide-valve and controlled by the screw rod or spindle N' and hand-wheel N², which may work in connection with an indicator n to show the position of the valve. This main valve is hollow, having openings n' at the front and back, and that face which closes over the supply-port is imperforate, while the other face shutting past the port leading to the distributing system is apertured, as at n², this providing a waterway from the distributing-pipes to the valve-chamber N³ in rear of the valve-seats at all times, whether the valve is open or closed.

Carried on one lateral face of the main valve is a spring-pressed relief-valve N⁴, which closes the port to the relief-pipe so long as the main valve is fully open, but which, by means of a lengthwise groove n³ or other suitable channel, establishes communication between the valve-chamber and said relief-pipe the instant the closing movement of the main valve commences and maintains it until such time as the main valve is again opened. Thus so long as the main valve is fully open the relief-pipe, with its alarm B', is cut off from the distributing-pipes; but coincidentally with any attempt to close the main valve it is opened to said distributing-pipes and their pressure-load. If now the relief-pipe is empty or without a pressure-charge or packed with a pressure of less weight than that normally in the distributing-pipes while cut off from the latter, the opening of the relief-valve will cause an excess of pressure in the relief-pipe and a decrease of pressure in the distributing-pipes, sounding the alarm of the one by a rising pressure and of the other by a falling pressure. It results from this arrangement that both alarm B and alarm B' will be sounded in case of tampering with the main valve; but the alarm or alarms B only will sound in case of the blowing of a fuse, thus locating the emergency.

It is to be noted that although the relief-pipe may be left without a load when cut off from the distributing-pipes and the alarm

will nevertheless sound with the movement of the pointer from zero whenever the communication is opened by the movement of the main valve, yet it is desirable that said pipe should be normally packed with a pressure somewhat exceeding that of the atmosphere, but below that in the distributing-pipes, so that should the pipe be cut with the intention of isolating the alarm the effect will be, on the contrary, to sound the alarm by reducing the pressure.

Having thus described my invention, what I claim as new therein, and desire to secure by Letters Patent, is—

1. In a pressure system, the combination with the distributing-pipes and main valve, of a relief-pipe closed off so long as the main valve is fully open, pressure-controlled alarm mechanism to which said relief-pipe leads, and means actuated in the closing movement of the main valve whereby said relief-pipe is opened to the pressure of the system.

2. In a pressure system, the combination with the distributing-pipes and main valve, of a relief-pipe closed off so long as the main valve is fully open, alarm mechanism operated both by a rise and a fall in pressure, to which said relief-pipe leads, means whereby said pipe is packed with a pressure above zero but less than the pressure of the system, and means actuated in the closing movement of the main valve whereby said relief-pipe is opened to the pressure of the system.

3. In a pressure system, the combination with the distributing-pipes and main valve, of a relief-pipe closed off so long as the main valve is fully open, pressure-controlled alarm mechanism at all times in connection with said pipes to be operated by variation of pressure therein, pressure-controlled alarm mechanism to which said relief-pipe leads, and means operated in the closing movement of the main valve whereby said relief-pipe is opened to the pressure of the system.

4. In a pressure system, the combination with the distributing-pipes and main valve, of alarm mechanism pipe-connected with said distributing-pipes and operated by either rise or fall of pressure, and a relief-valve opened in the incipient closing movement of the main valve.

5. In an electric alarm, the combination of a pressure-gage, an alarm-circuit, a double contact constantly connected with one side of the circuit and adjustable bodily around the axis of the pointer of said gage, an opposing contact connected with the other side of said circuit, and means whereby the circuit is closed by movement of the gage-spindle in either direction.

6. In an electric alarm, the combination of a pressure-gage, an alarm-circuit, a gapped contact-disk mounted upon and adjustable around the spindle which carries the pointer, and connected to one side of the circuit, and a stationary contact connected to the other side of the circuit.

7. In an electric alarm, the combination of a pressure-gage, an alarm-circuit, a gapped contact-disk mounted upon and adjustable around the spindle which carries the pointer, 5 and having knife-edges each side of the gap, a stationary contact consisting of two opposing springs with counter-setting contact-points mounted on a fixed part of the gage, and leads connecting the disk with one side of the circuit and the stationary contact with the other side.

8. In an electric alarm, the combination of a pressure-gage, the insulated contact-post forming an extension of its spindle, the gapped 15 contact-disk adjustable therearound and moving therewith, the connecting-spring resting on said post, and the stationary contact secured to a fixed part of the gage.

9. In an electric alarm the combination, of 20 a pressure-gage, an alarm-circuit, a rotatable post connected with the spindle of the gage and insulated therefrom, this post carrying a pointer and also a double-contact device ad-

justable bodily around the post, means constantly connecting the post with one side of the circuit, a stationary contact connected to the other side of the circuit, whereby the circuit will be closed by the double-contact device upon a movement of the gage-spindle in either direction.

10. In an electric alarm, the combination of a pressure-gage, an alarm-circuit, a double-contact device mounted on the gage-spindle and bodily adjustable independently thereof and the gage-pointer, means connecting this 35 double contact with one side of the circuit, and an opposing contact connected to the other side of the circuit and adapted to close the circuit upon a movement of the gage-spindle in either direction.

Signed by me at Chicago, Cook county, Illinois, this 6th day of July, 1899.

FRANK GRAY.
